UNITED STATES PATENT OFFICE.

PINY FRANK CHAIKIN, OF CONEY ISLAND, NEW YORK, ASSIGNOR TO ALFRED BLEYER & CO., OF NEW YORK, N.Y.

MACHINE FOR MAKING PAPER DISHES, &c.

1,191,665.

Specification of Letters Patent. Patented July 18, 1916.

Application filed March 24, 1916. Serial No. 86,335.

To all whom it may concern:

Be it known that I, PINY FRANK CHAIKIN, a citizen of the United States, and a resident of Coney Island, in the county of Kings and State of New York, have invented certain new and useful Improvements in Machines for Making Paper Dishes, &c., of which the following is a specification.

My invention relates to machines in which blanks of paper or other suitable fibrous or textile material are rendered dish-shaped or more or less concaved to form plates and other receptacles, the blanks being heated or "baked" during compression between male and female dies of suitable configuration to set the shape desired. In order to render the imparted shape permanent for all practical purposes for which such articles are designed it is necessary that the "baking" period *i.e.*, the time during which the blanks are held between the heated dies, be prolonged sufficiently to dry out (more or less) the moisture imparted to the blanks before compression to render them pliable and adaptive to the action of said dies. Heretofore machines of this character have been single acting in the sense that the reciprocating male die-head has been effective only at one extremity of its thrust or travel, the thrust cams of the machine being so formed and timed as to hold the male die head at rest for a prescribed "baking" period against the resistance of retractile springs which were relied upon to effect the open or return stroke of said male die head. This necessarily limited the speed and output of the machine, besides rendering its operation uncertain, since the retractile springs could not be relied upon to invariably separate the male and female dies owing to expansion of dies from overheating during long run or the sticking of moist blanks until sufficiently dried out to relieve binding, etc., so that in practice the male die head had to be frequently pried or forced away from the stationary female die head, or the machine stopped until the dies cooled off, or the blanks ceased to bind, the loss in time and product this involved frequently represents twenty five per cent of the theoretical efficiency or capacity of the machine if capable of being run uniformly and continuously.

Hence the object of my invention is to

obviate these difficulties, and to produce a better, more uniform and satisfactory product more rapidly and cheaply than heretofore, and to this end the invention consists in the specific construction and arrangement of parts claimed, distinctive features being a "duplex" or double faced male die head, and means for reciprocating it intermittently but positively between two opposed stationary female die heads, whereby the capacity of the machine is increased more than two fold while producing a superior article of manufacture, as hereinafter more fully set forth, incidental features of the invention being the means provided for insuring the ejection of the shaped blanks, the adjustment of stroke of the male die head with relation to the thickness of blanks heated, and other minor details of construction.

In the accompanying drawings, Figure 1, is a plan of my improved machine for making paper dishes, etc.; Fig. 2, is a side elevation thereof; Fig. 3, an end elevation thereof; Fig. 4, a vertical longitudinal sectional elevation taken upon plane of line 4-4, Fig. 1; Fig. 5, is a transverse section taken upon plane of line 5-5, Fig. 4; Fig. 6, is a face view of one of the stationary female die heads; Fig. 7, an end elevation of my duplex male die head, also illustrating the relation of the slides thereto; Fig. 8, a sectional detail of one of the slides, showing one of the stop blocks.

a, represents the longitudinal side members of the frame work of the machine generally, and *a'*, the cross members thereof.

B, *B'*, are the stationary die heads, also constituting practically cross members of the frame work. On the opposed inner faces of these stationary die heads *B*, *B'*, are mounted the female dies *c*, *c*, by any suitable means, as by the clamps *b*, *b*. The die plates are formed with blank rests *c'*, *c'*, to which the blanks *p*, (one or more at a time) are fed through the vertical guides *c*, *c*, Figs. 1, 2, 4, and 6.

As shown in the drawings, each stationary die head *B*, *B'*, accommodates two female dies *c*, *c*, although single dies may be used, or any plural number thereof may be provided according to size and capacity of the machine, the principle of construction and operation being the same in either case,

Each female die c , is provided with an ejector e , for insuring the discharge of the dished blanks at the proper time. Each ejector e , is preferably arranged centrally or axially with relation to its respective die c , being mounted in and through a cross web b' , of the die head B, B' , as shown more particularly in Fig. 4, and being formed with a collar e' , which contacts with the outer face 5 of the die head to limit the inward thrust of the ejector,—a spring e^2 , being interposed between said collar e' , and a cross bar e^3 , through which the outer end of the ejector e , passes, so that the spring e^2 , tends constantly to thrust the ejector inward. The 10 cross bar e^3 , is supported upon the stationary die head B, B' , by any suitable means as by the screw studs e^4 , shown. When the blank p , is forced into the female dies c , by 15 the male dies d , it is obvious that the ejectors e , will be forced back against the resistance of the springs e^2 , which latter will force the ejectors e, e' , to strip said female dies c , as soon as the male dies are retracted 20 therefrom.

Heating chambers b^2, b^3 , are formed in each stationary die head B, B' , in which are situated gas burners b^3, b^4 , supplied with gas through the branch pipe b^4 , connecting with 25 the main supply pipe b^5 , shown in Fig. 2.

The reciprocating male die head D , resembles the stationary female die heads in general construction except that it is provided with male dies d, d , on both faces and is 30 slidably supported between the horizontal ways a^2, a^3 , provided for the purpose on the frame work on either side thereof. That is to say it is formed with lateral slide arms d', d' , which fit between said ways, are rectangular in cross section, and of a width 35 equal to the horizontal thickness of the said die head D , or approximately so, in order to afford substantial supporting bearings as indicated in Figs. 4, and 5. Beyond the 40 bearing portions d', d' , of the slide arms are extensions d'', d'' , of reduced vertical thickness, which fit in longitudinal slots s, s , formed in the reciprocating slides S, S , supported in longitudinal horizontal grooves 45 a^3, a^3 , in the side members of the frame. The inner side of each slide S , and its groove a^3 , in the supporting side member of the frame are preferably of dove-tail construction, as shown particularly in Figs. 3, 50 5 and 5. The available or operative length of these slide slots s, s , is regulated by means of adjustable end blocks or stops s', s'' , controlled by set screws s^2, s^2 , and lock nuts s^3, s^3 , as shown in Fig. 2. Thus in said Fig. 2, 55 the distance between the left hand stop s'' , and the left hand side of the slide extension d'' , obviously represents the degree of play or lost motion that has to be taken up by the slide S , before the male die head D , will begin to move toward the right, and this ad-

justment of length of stroke of the male die head D , is provided for the purpose of compensating for variations in the thickness or number of blanks, p , to be introduced at each feed between the dies. It is to be understood of course, that the slots s , stop blocks s', s'' , and adjusting screws shown in Fig. 2, are duplicated in and on the slide S , on the other side of the machine. The movable die head D , is formed with heating 70 chambers d^2, d^3 , containing gas burners d^3, d^3 , supplied with gas through a flexible connection d^4 , (Fig. 2) communicating with the main gas pipe b^5 .

The two slides S , are reciprocated positively and simultaneously in either direction by means of cams K, K , one on each side of the machine, rigidly secured to a shaft K' , mounted in bearings in the side members of the frame,—the slides S, S , being formed with longitudinal slots s^4 , (as shown in Fig. 2) the side walls of which straddle the said cam shaft K' .

The cams K, K , are of the wiper type, acting alternately on contact rollers s^5, s^6 , on each of the slides S , to force the latter in opposite directions, $i. e.$, to effect the intermittent reciprocation of said slides. The cam shaft K' , is provided with a rigidly attached gear wheel k , and is rotated thereby 90 by means of a pinion f , (see Fig. 4) on the countershaft f' , mounted on and between bearings in the side members of the frame, said countershaft f' , being in turn provided with a rigidly attached gear wheel f^2 , 95 driven by a pinion g , on the power shaft g' ; see Fig. 2.

A sprocket wheel g^2 , on the power shaft g' , transmits motion by means of the sprocket chain g^3 , to the sprocket wheel h , (see Figs. 3, and 5) on the apron-driving shaft h' , mounted in horizontally adjustable bearing blocks (see Fig. 2) on the framework. Other sprocket wheels h^2, h^2, h^2 , (Fig. 5) on the apron-driving shaft h' , engage with sprocket chains h^3, h^3, h^3 , which carry the apron i , upon which the finished blanks drop from between the dies, to be transferred to a space or receptacle (not shown, reserved for their reception at the rear of the apron-driving shaft h' —the apron i , and its supporting sprocket chains h^3, h^3, h^3 , passing over coincident sprocket wheels on the idler shaft j , also mounted in horizontally adjustable bearing blocks, so that the chains and apron may be drawn taut. The apron i , also passes over and is supported by drums h^4, h^4 , on the apron driving shaft h' , between the sprocket wheels, and over corresponding drums (j' , Fig. 4) on the idler shaft j .

The reciprocating male die head D , is provided with ejectors d^5 , one common to each set of dies d, d , coincidently positioned on the opposite faces of the head, as shown 130

more particularly in Fig. 4, it being understood in this connection that in said view the dies and blank between them are shown as slightly separated for convenience of illustration, whereas in actual practice they would be in contact at this position of the cams K, K, and slides S, S. Each ejector d^5 is essentially a rod of slightly greater length than the combined thickness of the male dies d , d , and the die head D, and is mounted loosely in the medial web d^6 , of said die head, so that at or during the completion of each stroke or reciprocal thrust of the die head D, one end of the ejector 15 will contact with the blank or blanks between the male and female dies on the face of the head involved, as for instance the left hand face as shown in Fig. 4, thereby pushing said ejector d^5 , back toward the other side of the head D, so that it protrudes on that side sufficiently to insure the stripping of the male die thereon should the shaped blank or blanks resulting from the prior thrust of the head D, in the opposite direction have stuck to said male die,—the operation being of course reversed at the completion of the retractile stroke of the male die head D. The ejectors d^5 , may be flanged or headed at either extremity as shown in 20 Fig. 4, to increase bearing contact with the blanks, and to limit their extent of thrust in either direction.

The position of the parts shown in the main figures of the drawings being, as before intimated, that at the completion of the thrust of the slides S, S, from right to left, with the male dies on the left hand face of the reciprocating head D, acting in conjunction with the female dies on the opposed inner face of the stationary left hand die head B, to compress the blank or blanks p , interposed between them, it is obvious that the male die head D, will remain stationary in this position and relationship while the concentric peripheral parts of the cams K, K, from 1, to 2, (Fig. 2) are in contact with the left hand rollers s^2 , s^3 , of the slides S, S. It will also remain stationary in this position while the cams K, K, are acting against the right hand rollers s^2 , s^3 , of the slides S, S, until such time as the left hand stop blocks s'' , s''' , on the slides S, S, reach and contact with the left hand sides of the extensions d'' , d''' , of the beatings d' , d' , of the said movable head D. The extent of this lost motion is represented in Fig. 2, by the space between the stop block s'' , and the extension d'' , of the die head bearing shown therein, the same being equal on both sides of the machine, and this lost motion represents an additional period of rest during which the blanks p , are baked to perfection, i. e., until the moisture contained therein is driven off 55 and the dished blanks are hardened and

permanently shaped. It will be readily understood that this gain in the "baking" period is an important factor in the practical operation of the machine, whereby I attain a superior product while running the machine continuously, and in this connection also it may be stated that the positive means employed for insuring the stripping of the dished blanks from the dies is of importance, as well as the reciprocation of the slides S, S, and movable die head in both directions by positive means.

Another important factor in increasing the capacity and efficiency of the machine is the utilization of both thrusts of the male die head D, both the forward and the retractile strokes thereof, in the compression and baking of blanks,—this feature in conjunction with the positive motion of the male die head in both directions, and the positive stripping of the dies, more than doubles the capacity of my "duplex" apparatus as compared with the single acting retractile spring machines heretofore used. In other words the same results, the production of perfect permanent shaped dishes from which all moisture is eliminated so as to insure a positive and rigid set of the material, could only be attained by operating the old single acting machines at so slow a speed as to render the cost of production three times as great as compared with my duplex type of machine, and would involve an expenditure of time and labor that would be practically prohibitive in a commercial sense.

I have herein shown and described the male dies as mounted on the reciprocating die head D, and the female dies as mounted on the stationary die heads B, B', although it is obvious that this relative arrangement of male and female dies may be reversed if desired without departing from the spirit and intent of my invention in this respect. The arrangement shown however is preferable in that it facilitates the feed of the blanks to the dies, and because the fed blanks are at rest until ejected. It is to be noted also in this connection that by my construction and arrangement of parts one set of female dies may be fed with blanks while the blanks previously fed to the other set of female dies are being compressed and baked, whereas heretofore the operation had to wait until the retractile movement of the male dies before feeding new blanks, and it was necessary sometimes to pry the male dies away from the female dies before they could be stripped for the purpose.

What I claim as my invention and desire to secure by Letters Patent is,

1. In a machine of the character designated, the combination of two stationary die heads and dies and an intermediate reciprocating die head carrying dies adapted to

gage alternately with the dies in the stationary die heads, together with means for heating the dies, for the purpose described.

2. In a machine of the character designated, the combination of two stationary die heads and dies, an intermediate movable die head carrying dies adapted to engage alternately with the dies on the stationary heads, and means for positively reciprocating said intermediate die head, together with means for heating the dies, for the purpose described.

3. In a machine of the character designated, the combination of two stationary die heads provided with female dies, and an intermittent reciprocatory die head carrying male dies adapted to engage alternately with the female dies in said stationary die heads, together with means for heating the dies, for the purpose described.

4. In a machine of the character designated, the combination of two stationary die heads provided with female dies, an intermediate movable die head carrying male dies adapted to engage alternately with the female dies on the said stationary die heads, and means for positively reciprocating said intermediate die head, together with means for heating the dies, for the purpose described.

5. In a machine of the character designated, the combination of two stationary die heads and dies, an intermediate die head movably supported upon the frame of the machine, and positively reciprocated slides adapted to engage and move said intermediate die head for a portion only of their thrust in either direction together, with means for heating the dies, for the purpose described.

6. In a machine of the character designated, the combination of two stationary die heads and dies, an intermediate die head movably supported upon the frame of the machine, positively reciprocated slides

adapted to engage and move said intermediate die head for a portion only of their thrust in either direction, and adjustable means on said reciprocatory slides for regulating the extent of lost motion between them and the said intermediate die head, together with means for heating the dies, for the purpose described.

7. In a machine of the character designated, the combination of two stationary die heads and dies, an intermediate movable die head carrying dies adapted to engage alternately with the dies on said stationary die heads, means for positively reciprocating said intermediate die head, and an ejector slidably mounted on said movable die head and of greater length than the thickness thereof and adapted to be operated alternately in either direction by contacting with the stationary dies at the termination of the thrust of the reciprocatory die head in either direction, together with means for heating the dies, for the purpose set forth.

8. In a machine of the character designated, the combination of two stationary die heads and dies, an intermediate movable die head carrying dies adapted to alternately engage with the dies on said stationary die heads, means for positively reciprocating said intermediate die head, elastic resilient ejectors on the stationary die heads adapted to be actuated by said reciprocatory die head, and an ejector slidably mounted on said reciprocatory die head and of greater length than the thickness thereof and adapted to be operated alternately in either direction by contacting with the stationary dies at the termination of the thrust of said reciprocatory die in either direction, together with means for heating the dies, for the purpose set forth.
